INSULATOR

John J. Taylor, Barberton, Ohio, assignor to The
Ohio Brass Company, Mansfield, Ohio, a cor-
poration of New Jersey

Application March 20, 1934, Serial No. 716,476

9 Claims. (Cl. 173—318)

This invention relates to electrical insulators and particularly to insulators subjected to relatively high bending moments such as pin type, post and pillar insulators.

5 One object of the invention is to provide an insulator in which relative movement of the parts, due to differential expansion or contraction will take place in the direction of the bearing surfaces of the parts and not transverse to such surfaces, so as to avoid stresses in the connected parts.

Another object of the invention is to provide an insulator in which the bearing surfaces of the connected parts are advantageously disposed for 15 resisting bending moments.

A further object of the invention is to provide a device of the class named which shall be of improved construction and operation.

Other objects and advantages will appear from 20 the following description.

The invention is exemplified by the combination and arrangement of parts shown in the accompanying drawing and described in the following specification, and it is more particularly pointed 25 out in the appended claims.

In the drawing the figure is a vertical sectional view of an insulator showing one embodiment of the present invention.

Electrical insulators are usually made up of 30 metal and dielectric parts connected together by a binding material such as cement. Porcelain is extensively used as a dielectric material and since the coefficient of expansion of porcelain for temperature changes is different from 35 that of most metals, changes of temperature cause differential expansion and contraction of the parts; and unless the insulator is properly designed to accommodate such differential expansion and contraction, stresses are apt to be 40 set up in the porcelain which may produce cracking, since porcelain is a fragile material.

In the present invention the bearing surfaces between the connected parts are so disposed that relative movement takes place along the surfaces 45 rather than transverse thereto, thus avoiding stresses due to expansion and contraction. The arrangement of the surfaces is particularly advantageous in insulators subjected to bending moments.

50 In the drawing the numeral 10 designates a supporting pin for an insulator, on which is mounted a dielectric member 11, which may be of porcelain and to which a metal cap 12 is secured. Cement 13 and 14 is used for connecting the 55 porcelain member to the respective fittings. The

pin 10 is provided with a plurality of conical bearing faces 15, 16, 17 and 18 which engage the cement 13. All the other faces of the pin in contact with the cement are relieved by a coating 19 which may be of some form of compressible material, such as cork, or material which will exclude the cement and afterwards shrink in drying, such as paste. Any coating which will relieve the surfaces of pressure and is otherwise satisfactory may be used.

5 The upper end of the pin may be closed by a plaster block 20 to prevent entrance of the cement into the interior of the pin. The cap is also provided with a plurality of conical bearing faces 21, 22, 23 and 24, and the other surfaces of the 15 cap contacting with the cement are relieved in a manner similar to the surfaces 19 of the pin. All of the bearing surfaces on the cap and pin have a common apex at a point 25 on the axis of the insulator and centrally disposed vertically relative to the bearing faces.

20 Expansion or contraction of the cap and pin may be regarded as taking place along lines radiating from the point 25 and any expansion of either the cap or pin along these surfaces will 25 be in the direction of the surface of contact with the cement and not transverse to these bearing surfaces. Relative movement between the fittings and the cement on other surfaces of the fittings will not produce pressure since all of the 30 other surfaces are relieved. It will thus be seen that any expansion or contraction of the metal fittings may be accommodated by relative movement of the bearing surfaces in the direction of these surfaces and that there will therefore be 35 no pressure set up at any bearing surface through such expansion or contraction; and since all the other surfaces are relieved, the entire differential expansion or contraction of the parts will be accommodated without setting up stresses in 40 the connected parts.

The bearing surfaces are also advantageously arranged for opposing bending moments. If a bending moment tends to produce relative rotation of the parts about the point 25, the pressure 45 produced between the contacting surfaces will all be normal to these surfaces due to the radial relation of the bearing surfaces to the fulcrum point 25. Of course, if the fulcrum point is above or below the point 25, the bearing surfaces will not be 50 exactly normal to the forces imposed upon them but nevertheless they will be approximately normal to the pressure so that the surfaces are advantageously disposed to oppose bending moments to which the insulator is subjected.

I claim:

1. An insulator comprising a dielectric member having a recess therein, a pin disposed in said recess, a cap surrounding a portion of said dielectric member and cement connecting said dielectric member with said pin and cap, said pin and cap each having a plurality of oppositely directed spaced bearing faces, all of which bearing faces radiate from a common point. 5
10. 2. An insulator comprising a dielectric member having a recess therein, a pin disposed in said recess, a cap enclosing the portion of said dielectric member surrounding said recess, cement connecting said dielectric member with said cap and pin, said cap and pin being disposed in overlapping relation, said cap and pin each having spaced oppositely directing bearing faces, the bearing faces of said pin and cap radiating from a common point on the axis of said pin, the other surfaces of said pin and cap in contact with the cement and not radiating from said common point being relieved to prevent pressure between the cement and said pin and cap on said relieved faces. 15
15. 3. An insulator comprising connected parts subject to differential expansion and contraction, said parts having cooperating bearing surfaces formed by surfaces of frustums opposed in direction and having a common apex, adjacent surfaces of said parts other than the surfaces of said frustums having clearance therebetween to restrict the bearing between said parts to the surfaces of said frustums. 20
20. 4. An insulator comprising connected parts subject to differential expansion and contraction, one of said parts being disposed in a recess in the other, said parts having cooperating bearing surfaces forming surfaces of opposed frustums having a common apex, said parts having surfaces connecting the surfaces of said frustums, said connecting surfaces having clearance therebetween to prevent bearing contact between said connecting surfaces. 25
25. 5. An insulator comprising a dielectric member and a metal member subject to differential expansion and contraction, one of said members extending into a recess in the other, said members having cooperating bearing surfaces forming surfaces of opposed frustums having a common apex, adjacent surfaces of said respective parts other than the surfaces of said frustums having clearance therebetween and the cooperating bearing surfaces of said frustums being unbonded to each other. 30
35. 6. An insulator comprising a dielectric member, a metal fitting for said dielectric member, said dielectric member and fitting being subject to differential expansion and contraction, said fitting having bearing surfaces thereon forming surfaces of opposed frustums having a common apex, cement interposed between said dielectric member and fitting and providing bearing surfaces conforming to the surfaces of the frustums on said fitting but being unbonded to said surfaces, adjacent surfaces of said fitting and cement other than the surfaces of said frustums having clearance to restrict the bearing between said fitting and cement to the surfaces of said frustums. 35
40. 7. An insulator comprising a dielectric member and a metal fitting, one of which extends into a recess in the other, said metal fitting having conical bearing surfaces thereon forming surfaces of opposed frustums having a common apex, cement interposed between said dielectric member and fitting and conforming to the conical bearing surfaces on said fitting but being unbonded thereto, adjacent surfaces of said fitting and cement other than the surfaces of said conical frustums having clearance therebetween to restrict the bearing between said dielectric member and fitting to said conical frustums. 40
45. 8. An insulator comprising a dielectric member having a recess therein, a metal pin extending into said recess and differentially expansible and contractible relative to said dielectric member, said pin having conical bearing surfaces thereon forming surfaces of opposed frustums having a common apex, said dielectric member having bearing surfaces thereon conforming to and cooperating with the surfaces of said frustums, the surfaces of said frustums constituting the entire bearing connection between said pin and dielectric member. 45
50. 9. An insulator comprising a dielectric member having a recess therein, a pin extending into said recess and having conical bearing surfaces thereon forming opposed frustums having a common apex, cement interposed between said pin and dielectric member and conforming to the bearing surfaces of said frustums on said pin but being unbonded thereto, adjacent surfaces of said pin and cement other than the surfaces of said frustums having clearance therebetween to restrict the bearing between said pin and cement to said conical frustums. 50
